UNITED STATES PATENT OFFICE.

LOUIS J. JACQUEMIN, OF KENNEBUNK, MAINE, ASSIGNOR TO ELLIOTT ROGERS, OF KENNEBUNK, MAINE.

COUNTER-BLANK-CUTTING MACHINE.

1,315,367.

Specification of Letters Patent. Patented Sept. 9, 1919.

Application filed May 19, 1917. Serial No. 169,757.

To all whom it may concern:

Be it known that I, LOUIS J. JACQUEMIN, a citizen of the United States, residing at Kennebunk, in the county of York and State 5 of Maine, have invented certain Improvements in Counter-Blank-Cutting Machines, of which the following description, in connection with the accompanying drawings, is a specification, like reference characters on 10 the drawings indicating like parts in the several figures.

This invention relates to machines for making heel stiffeners or counters for boots and shoes and is particularly concerned with 15 the preparation of fiber counter blanks for the molding operation.

For the purpose of explaining more clearly the objects of this invention certain steps in the process of making counters are 20 illustrated in the first sheet of the accompanying drawings, in which:

Figure 1 is an angular view of a rough counter blank;

Fig. 2 is a cross sectional view on the line 25 2—2, Fig. 1;

Fig. 3 is an angular view of a finished counter blank; and

Figs. 4 and 5 are cross sectional views taken, respectively, on the lines 4—4 and 30 5—5, Fig. 3.

As is well understood by those skilled in this art, a large percentage of the counters used in shoes, particularly in the lower priced shoes, are made of material known 35 in the trade as "fiber" or "leatherboard". The sheets of this material are first cut up into strips of the proper width for the counters, the cutting being done by knives which bevel the opposite edges of the strip, 40 and these strips are then cut up into sections of the required length. One of these sections or rough blanks is indicated at A in Figs. 1 and 2, the beveled surfaces at the edges being shown at *a* and *b*. This rough 45 blank is then subjected to further cutting operations which produce the finished blank B, Fig. 3. These operations consist in cutting the blank to the required curved outline, making a beveled face *c* along the upper curved edge of the blank and forming long bevels *d* at the opposite 50 ends of the blank. The formation of the bevels *d* thins the entire end portions of the blank and makes these portions more flexible 55 than is the body of the blank. In the mold-

ing operation the lower edge, along which the bevel *b* is formed, is turned under or crimped so that it will lie over the tread face of the heel part of the last; and the ends *d* and the upper edge *c* are beveled to give them 60 the required degree of flexibility. The body or main heel part of the counter, of course, is designed to be very stiff and firm.

It has been customary heretofore to perform the cutting operations necessary to 65 produce the finished blank B from the rough blank A in two steps, the first step consisting in cutting the blank A to form the curved edge and simultaneously therewith forming the beveled surface *c*, and the second operation 70 consisting in forming the wide bevels *d* on the two end portions of the blank. The first operation usually is performed by placing the rough blank A in a suitable matrix provided with a shearing member having 75 an outline corresponding to the curved outline desired in the finished blank and shaped to deflect the margin of the blank adjacent to this curved edge into the path of travel of a knife. The knife and matrix are then 80 relatively moved to cause the knife to bevel off the deflected stock and shear the blank against the shearing member with which the matrix is provided. The blank is next 85 placed in another machine usually equipped with a pair of planes or shaving knives which form the wide bevels *d* at the opposite ends of the blank. The first of these operations usually is referred to in the trade 90 as cutting and beveling the blank; and the second operation, namely, that of forming the bevels *d*, is termed "releasing" the blank.

While it is possible to bevel and release a leather counter blank at a single operation, the machines by which this operation is performed are not adapted to perform the same operations on a fiber or leatherboard blank because of the peculiar laminated or ply structure of this material, and it has always 100 been the practice, so far as I am aware, to perform the releasing operation on a fiber blank independently of the cutting and beveling operation. It is the chief object of the present invention to devise a machine which will perform both of these operations 105 on fiber counter blanks.

The invention in its preferred form involves a novel form of matrix and a novel construction of knife, these devices being arranged to coöperate with each other to 110

produce the desired result. The several features of the invention will be readily understood from the following description of the preferred embodiment thereof and 5 will be particularly pointed out in the appended claims.

Referring now to the remaining figures of the accompanying drawings:

Fig. 6 is a front elevation of an old form 10 of counter cutting machine modified to embody the present invention;

Fig. 7 is an elevation of the novel form 15 of matrix and knife provided by this invention;

Fig. 8 is a vertical cross sectional view on the line 8—8, Fig. 7;

Fig. 9 is a vertical cross sectional view on the line 9—9, Fig. 7; and

Fig. 10 is a central cross sectional view 20 through the parts of the machine shown in Fig. 6.

The drawings show this invention as applied to the cutting machine shown and described in Patent No. 513,242, granted January 23, 1894, to George F. Moore. Machines constructed substantially in accordance with the disclosure made in this patent have been in use for a great many years, 25 these machines, however, being equipped with an automatic feeding mechanism that feeds rough blanks one at a time into the cutting mechanism. For a complete understanding of the construction and operation of this machine reference should be made 30 to said patent. For the purposes of the present application only a very brief description of the machine is necessary. The machine shown includes a frame 2 provided with ways in which a cross head 4 reciprocates. This cross head carries a die or 35 matrix 6; and a knife 8, which co-operates with the matrix, is bolted to a cross piece 10 that forms part of the machine frame. A clamp 12 is mounted upon a bracket 14 40 which is pivoted to the slide or cross head 4 at 16 so that this clamp can swing relatively to the matrix but reciprocates with it. Connecting rods 18, pivoted to opposite sides of the slide 4 and operated by eccentric 45 pins on disks 20 that rotate with the shaft 22, give the matrix its reciprocating movement toward and from the stationary knife 8. As the matrix is moved up and down the clamp 12 is moved in and out relatively 50 to the matrix to clamp and release the blank by means of cam rolls, one of which is shown at 24, Fig. 10. These rolls are mounted on studs supported in ears depending from the bracket 14 and they run in stationary cam paths 26 formed in a part of 55 the machine frame, this path being designed to move the clamp at the desired times in the stroke of the matrix. The blanks may be fed into the machine either automatically 60 or by hand and gages 28 are provided to

position the blanks properly in readiness to be clamped in the matrix by the member 12. All these parts are constructed and arranged to operate substantially as shown in the Moore patent, above designated, and the 70 illustration and description of them here are made merely for the purpose of making a clear disclosure of one embodiment of the present invention.

The matrix, as best shown in Figs. 7, 8 75 and 9, comprises a shearing member 30 shaped to conform to the desired outline of the curved edge of the finished blank and mounted in a slot 31 formed in the bed of the matrix. A series of bolts 32, threaded 80 through the outer wall of this slot 31, bear against the member 30 and hold it in its operative position. The matrix is provided with a central depression 34 which corresponds in shape and dimensions with that of the central raised part of the finished blank 85 B. It is also provided with a relatively narrow raised portion 36 just back of the middle part of the shearing member 30 and with wide raised parts 38 or shoulders near the 90 opposite ends of the matrix and into which the ends of the part 36 merge.

The knife 8, as clearly shown in Figs. 6 and 7, has a forward cutting edge *e* and two lateral cutting edges *f* that extend diagonally backward from the ends of the portion *e* so that the part *e* corresponds to the top and the parts *f* to the two sides of a trapezoid. The entire cutting edge lies in a plane which, in this machine, is the plane of the 100 shearing edge of the member 30, this plane being parallel to the plane of the reciprocating movement of the matrix. It will be noted that the part *e* of the edge of the knife 8 is shorter than the narrow raised 105 portion 36 of the matrix and that the knife, at its base, is slightly longer than the distance between the extreme ends of the curved shearing member 30. It will also be seen that when a blank, such as that 110 shown at A in Fig. 1, is properly placed in the matrix 6 and is clamped in the matrix by the plate 12, it will rest in the matrix substantially as shown in Fig. 7 overlying the entire length of the cutting edge of the 115 shearing member 30. The central portion of this blank will be depressed below the plane of the shearing edge of the member 30 by means of the clamp 12, as clearly 120 shown in Figs. 8 and 9, but the narrow marginal portion along the curved edge of the blank will be deflected into a position above the plane of the shearing edge of said member 30, as will also the wide end portions of the blank that overlie the shoulders 38 125 of the matrix. Consequently, when the matrix carries the blank under the knife 8, the forward edge *e* of the knife will cut into the upper curved margin of the blank A, forcing it firmly against the face 36 of 130

the matrix, and shearing off the parts of the blank that lie above the plane of the shearing edge of the member 30. Figs. 7 and 8 show the parts when the edge *e* of the 5 knife has cut about half way through the upper margin of the blank. The knife preferably is so proportioned that after it has partly completed the beveling of the upper margin of the blank, the inclined edges *f* of the 10 knife will begin to cut into the blank near its opposite ends and immediately above the inner edges of the shoulders 38 of the matrix. The knife is shown in Figs. 7 and 9 just after it has begun to cut into 15 the opposite end portions of the blank to form the beveled surfaces *d* of the finished blank (see Fig. 3). As the matrix 6 continues to move downwardly and thus transfers the points of operation of the knife forward 20 across the blank A, the forward edge *e* of the knife will first complete the formation of the bevel *c*, Fig. 3, of the blank and cut the blank to the outline of the edge 25 of the shearing member 30 and the points of operation of the two opposite edges *f* will then travel along the shearing blade 30 in opposite directions toward the ends 35 of the blank and over the shoulders 30 until the entire cutting and beveling operations 40 have been completed.

It will now be understood that this single operation not only cuts the blank A to the desired outline, but that the part *e* of the knife forms the bevel *c* and the parts *f* 45 form the two bevels *d* at the opposite ends of the blank. In other words, this mechanism at one operation cuts the blank to the desired outline, bevels it and releases it. Attention is particularly directed to the 50 fact that, by so proportioning the knife that the edge *e* begins to form the bevel *c* before the lateral edges begin to form the bevels *d*, the knife is enabled to aid the clamp 12 in holding the blank properly in the matrix 55 while the cutting operations on the blank are being performed. This arrangement also tends to equalize the forces exerted on the blank by the knife, since the two lateral edges *f* act simultaneously on the opposite 60 end portions of the blank and cut in opposite directions toward the ends of the blank, so that tendency of one lateral edge to crowd the blank toward the end of the matrix is counteracted by the corresponding 65 tendency of the opposite lateral edge of the knife. That is, the lateral edges of the knife act on the blank to urge the opposite ends of the blank away from each other but since the knife cuts both ends of the blank 70 simultaneously, the drag of one edge tending to move the blank endwise will be equalized by the drag of the other edge tending to move the blank endwise in the opposite direction. The edge portion *e* of the knife 75 bevels the blank in exactly the same way

that does the corresponding edge of the knife in the old types of machines; but the lateral edges *f* operate on the blank by making draw cuts in the opposite end portions of the blank and the knife thus is 80 enabled to cut the blank smoothly and easily to form smooth beveled surfaces *d* on the blank, without any of the tendency to tear and dig the blank which has been experienced in the efforts heretofore made along 85 this line.

It will be noted that the knife 8 is recessed behind its cutting edge, as clearly indicated at *g* in Figs. 8 and 9, so that ample clearance is provided for the cutting 90 edge of the knife.

I believe that I am the first to devise a machine in which a fiber or leatheroid counter blank can be beveled and released at a single operation. It is obvious that the machine of this invention eliminates the necessity for a separate machine for performing the releasing operation and that it saves one handling of the blanks which heretofore has been required. 95

What is claimed as new is:—

1. In a counter blank cutting machine, the combination of a knife, a matrix having a curved edge, and means for relatively moving said knife and matrix to enable the knife to operate on a blank in the matrix, said matrix being constructed to deflect a narrow marginal portion along the upper curved edge of the blank and wide end portions of the blank into position to 100 be cut by the knife, and said knife having portions shaped to bevel said deflected edge and end portions and to cut said end portions in directions toward the opposite ends of the counter. 105

2. In a counter blank cutting machine, the combination of a matrix comprising a shearing member shaped to conform to the curved upper edge of a counter blank and having portions constructed to deflect the 110 marginal portion of the blank along said edge and wide portions near the opposite ends of the blank into a position above the plane of said shearing member, a clamp operative to hold a blank in said matrix, a knife having a cutting edge corresponding substantially to the outline of the top and sides of a trapezoid and co-operating with said matrix to cut away the parts of the counter blank that project above the plane 115 of said shearing member, and mechanism for relatively moving said knife and matrix. 120

3. In a counter blank cutting machine, the combination of a knife having a forward 125 cutting edge extending at substantially right angles to the direction of the cutting stroke and having lateral edges extending diagonally backward from the ends of said forward edge, a matrix constructed to deflect 130

a narrow portion at the upper edge of a counter blank into the path of said forward cutting edge and having parts shaped to deflect wide end portions of the blank into position to be beveled by said lateral edges, means for holding a counter blank in said matrix, and means for relatively reciprocating said matrix and knife.

4. In a counter blank cutting machine, the combination of a matrix, a clamp arranged to hold a counter blank having a curved upper edge in said matrix, a knife, and mechanism for giving said matrix and knife a relative movement to enable the knife to operate on the blank held in the matrix, said knife and matrix being constructed and arranged to cause the knife to bevel the middle portion of the curved edge of the blank and thereafter to release the ends of the blank, and said knife being operative to aid the clamp in holding the blank in the matrix while the releasing action is taking place.

5. In a counter blank cutting machine, the combination of a matrix, means for holding a counter blank in said matrix, and a cutting mechanism coöperating with said matrix while the blank is held therein to bevel the upper edge of the blank and to release the end portions of the blank, said mechanism being arranged to start said beveling operation just before it begins said releasing operation.

6. In a machine for cutting fiber counter blanks, the combination of a matrix comprising a shearing member shaped to conform to the curved upper edge of a counter blank and having portions constructed to deflect the marginal portion of the blank along

said edge and the entire end portions of the blank into a position above the plane of said shearing member, a clamp for holding said blank in said matrix, and cutting means operative on the blank while it is in said matrix to cut away said deflected portions and thus to bevel said upper edge and also to release both ends of the blank, said cutting means being constructed and arranged to perform said releasing operation by making substantial simultaneous cuts across the end portions of the blank in directions urging the opposite ends of the blank away from each other.

7. In a machine for cutting fiber counter blanks, the combination of a matrix comprising a shearing member shaped to conform to the curved upper edge of a counter blank and having portions constructed to deflect the marginal portion of the blank along said edge and the entire end portions of the blank into a position above the plane of said shearing member, a clamp for holding said blank in said matrix, and cutting means operative on the blank while it is in said matrix to cut away said deflected portions and thus to bevel said upper edge and also to release both ends of the blank, said cutting means being constructed and arranged to perform said releasing operation by making draw cuts toward the opposite ends of the blank substantially simultaneously, whereby the drag of the cutting means on one end will be equalized by the drag on the other end.

In testimony whereof I have signed my name to this specification.

LOUIS J. JACQUEMIN.
